DISTANCE MEASURING INSTRUMENT

Wallace D. Evans, Jr., Malibu, Calif., assignor to
Rotatape Corporation, Santa Monica, Calif.

Filed Jan. 21, 1971, Ser. No. 108,679

Term of patent 14 years

Int. Cl. D10—04

U.S. Cl. D52—6

FIG. 1 is a left, rear perspective view of a distance measuring instrument showing my new design;

FIG. 2 is a right, rear perspective view of FIG. 1 where-
in the handle is in an extended position;

FIG. 3 is a left side elevational view of FIG. 1; and
FIG. 4 is a front elevational view of FIG. 1.

I claim:

The ornamental design for a distance measuring in-
strument, substantially as shown and described.
